UNITED STATES PATENT OFFICE.

DANIEL BURROWS, OF BROOKLYN, ASSIGNOR TO THE J. L. MOTT IRON WORKS, OF NEW YORK, N. Y.

ATTACHMENT FOR OPERATING CISTERN-VALVES FOR WATER-CLOSETS.

SPECIFICATION forming part of Letters Patent No. 299,341, dated May 27, 1884.

Application filed December 3, 1883. (No model.)

To all whom it may concern:

Be it known that I, DANIEL BURROWS, of Brooklyn, in the county of Kings and State of New York, have invented an Attachment for 5 Operating Cistern-Valves for Water-Closets, of which the following is a specification.

The valves of water-closet cisterns have been opened by a connection to the door of the closet, or to a platform, or to the seat. 10 These devices are liable to operate irregularly, the valve being opened to a greater extent when the door is opened wider or the platform is depressed by a heavier person. Springs also are often used, and these are liable to lose 15 their elasticity or to break.

My invention consists in the combination, with the chain or connection passing to the cistern-valve, of a double-acting latch and a slide-connection to the door of the closet or 20 other moving device, the parts being constructed so that the latch is drawn along with and by the slide, and the closet-valve thereby opened. The latch and slide are then automatically disconnected, and the slide is free 25 to move back or forth with the door without acting upon the latch until the door is closed, or nearly so, which causes the slide to re-engage with the sliding latch, ready for operation when the door is again opened.

30 In the drawings, Figure 1 is an elevation of the attachment with the cover-plate removed. Fig. 2 is a plan view sectionally at the line *x x*, and Fig. 3 is a cross-section at *y y*.

The plate *a* is to be fastened to the wall or 35 partition *A* of the closet, and said plate *a* has projecting from its surface the studs 1 2 3 4.

The compound sliding latch *b* is provided 40 with slots or mortises for the pins 3 and 4, so that the latch can slide back and forth upon the pins. At one end of the latch *b* is the joint or connection *c*, for the end of the chain or rod *c'*, which passes by pulleys or bell-crank levers to the lever of the cistern-valve in any usual or desired manner. At the other end of 45 *b* is the latch-head *d*.

The slide-bar *e* is slotted longitudinally at *i*. There is a zigzag in such slot. The bar *e* is supported by and slides upon the pins 1

and 2. At one end is the latch *f*, engaging the latch *d*, and at the other end there is a 50 joint, *g*, to which the link *h* is connected, which link is pivoted at the other end to the door *K* or other moving device by which the person operates the parts on entering or leaving the closet.

55 The cap-plate *L* is adapted to cover the slide and compound latch and to retain the parts in place. It is preferably slotted near one end for allowing the link *h* to move with the slide unobstructed, and near the other end for 60 the joint *c*. The cap-plate will usually be connected to the plate *a* by screws or rivets, and there are screws at 6 6 to attach the plate and case to the partition or wall.

When the door of the closet is closed and 65 the parts in their normal position, the latches *d f* are engaged, as seen in Fig. 1. When the door is opened, the bars *b* and *e* are drawn along endwise by the link *h*, and the offset or zigzag in the slot at *i* causes the pin 2 to 70 disengage the latch *f* from the latch *d*, and the slide-bar *e* is then free to be moved either way as the door may be opened or closed. In the movement of the latch-bar *b* the chain or cord to the cistern-valve is pulled and the 75 valve opened. As soon as the latches *d f* separate, the latch-bar *b* is drawn back by the weight of the valve or its lever, and when the door is closed the slide-bar *e* moves along endwise until the latch *f* runs under the latch *d* and 80 raises the same, the slot in the latch-bar *b* being widened at *o*, beneath the stud 3, so as to allow of this latch *d* lifting, after which it drops and engages the latch *f*, ready for the next operation when the door is opened.

85 I claim as my invention—

1. The latch-bar *b*, with the latch *d* at one end and a connection at the other end for the chain or wire to the cistern-valve, in combination with the slide-bar *e*, latch *f*, and link 90 *h*, or connection to the door or moving device, for the purposes and substantially as set forth.

2. The slotted latch-bar *b*, latch *d*, plate *a*, and studs 3 and 4, in combination with the 95 slide-bar *e*, slotted longitudinally and zigzag,

and the studs 1 and 2 on the plate *a*, and the cover or case *L*, substantially as set forth.

3. The latch-bar *b*, slotted and having the end of the slot widened at *o*, in combination with the plate *a*, studs 3 and 4, the slide-bar *e*, with the latch *f*, the zigzag or offset at the slot in said bar *e*, and the studs 1 and 2, substantially as set forth.

Signed by me this 19th day of November,
A. D. 1883.

DANIEL BURROWS.
